UNITED STATES PATENT OFFICE.

SAMUEL F. HILGENFELD, OF SAN FRANCISCO, CALIFORNIA.

BRACKET.

1,320,329.

Specification of Letters Patent. Patented Oct. 28, 1919.

Application filed March 30, 1916, Serial No. 87,878. Renewed October 12, 1917. Serial No. 196,343.

To all whom it may concern:

Be it known that I, SAMUEL F. HILGENFELD, a citizen of the United States, residing in the city and county of San Francisco, 5 State of California, have invented a new and useful Improvement in Brackets, of which the following is a specification.

The invention relates more particularly to a bracket for attachment to a metallic wash tub, sink, or the like, to provide a securing member to which a wringer may be clamped.

Metallic wash tubs and sinks are almost universally formed with an outstanding horizontal flange around their upper edges, and these flanges make it very difficult if not impossible to secure a clothes-wringer in position, and the primary object of this invention is to provide a bracket of extremely 15 simple and practical construction which may be bolted or otherwise secured to the flange of the tub or sink and which will afford a clamping base to which the clothes-wringer may be secured.

Another and more specific object of the invention is to provide a bracket of this nature which may be formed from a single piece of sheet metal with a few stamping and bending operations, which may be carried on at a small cost.

With these and other objects in view, the invention consists in certain novel features of construction, combination and arrangement of parts as will be hereinafter fully 30 described, illustrated and claimed.

In the drawing:

Figure 1 is a perspective view showing a clothes-wringer attached to a tub through the medium of my improved brackets.

Fig. 2 is a detail perspective view showing the brackets attached to the flange of the tub, and

Fig. 3 is a fragmentary sectional view on the plane of line III—III of Fig. 2.

Referring in detail to the drawings by numerals, 1 designates a metallic tub having an outwardly extending horizontal flange 2 around its upper edge and 3 designates a clothes-wringer of the ordinary construction 45 which is provided with the customary arm. 4 and clamping screws 5.

The flange 2 makes it impossible to clamp the wringer to the side of the washtub and, therefore, the brackets 6 forming the subject 50 matter of this invention have been designed for attachment to the flange 2 to provide a

base to which the clothes-wringer may be clamped. The brackets are preferably used in pairs, one for each leg of the wringer, and each bracket is formed from a single piece 60 of sheet metal, bent to provide a body portion having an upstanding clamping base formed with the inner wall 7 and the outer parallel wall 8, which walls are connected at their upper edges by the horizontal wall 65 9. The lower edge of the wall 7 is bent inwardly at substantially right angles providing the horizontal flange 10, and the material forming the bracket is bent inwardly from the bottom of the wall 8 to provide the 70 base wall 11 on the forward or inner edge of which is formed the angular flange 12 which extends downwardly across the edge of the tub flange 2 and then under said flange as a basewall parallel to basewall 11 in engagement with the lower face thereof as clearly shown. Side walls 13 are formed on the side edges of the vertical wall, extend downwardly and inwardly across the side edges of the wall 7 and have their lower end 80 edges turned under the wall 11 as shown in Fig. 3. The wall 11 is offset upwardly a slight distance from the flange 2 to provide a channel or pocket for the inturned ends 14.

The side walls 13 are triangular in shape 85 and their lower portions extend inwardly beyond the side edges of the walls 7 and these walls and the flange 10 form a pocket in which one of the legs of the wringer will fit. A bolt 15 extends through the flange 90 10, wall 11, flange 2 of the tub and the bottom of the angular flange 12, and is secured in position by the nut 16, thus providing a means for securing the bracket to the flange 2. By spacing the walls 7 and 8 a better 95 clamping base is provided for engagement with the clamp 5 and by off setting the wall 11 to accommodate the inturned end 14, a good even surface is provided for engagement with the top flange 2.

From the foregoing description taken in connection with the drawings, it will be seen that I have provided a very practical, substantial, and cheaply manufactured wringer bracket which may be quickly secured to the flange of a tub or sink and which is provided with a pocket to receive one of the wringer legs and which is also provided with clamping base to which the wringer may be clamped.

While I have shown and described the preferred embodiment of my invention, it

will be understood that minor changes in construction and arrangement of parts may be made without departing from the spirit and scope of the invention claimed.

5 What I claim and desire to secure by Letters Patent is:

1. A wringer bracket comprising an integral strip of sheet metal bent to form an upstanding standard; parallel clamping 10 base walls bent at an angle to said standard and forming a channel to receive a supporting member, and side walls bent at an angle to said standard and having edges terminating at said channel.

15 2. A wringer bracket including a body having an upstanding standard consisting of two spaced, connected, parallel walls, one of said walls having an extension at substantially right angles thereto to form a 20 bottom wall; the other wall being bent in a plane parallel to the extension of the first wall and engaging therewith; side walls on said standard extending beyond one face thereof forming a pocket, said side walls 25 having their lower ends turned under the lower face of the bottom wall; an angular flange formed on one edge of said bottom wall providing a channel adapted to receive a supporting member and means for securing 30 said bracket onto said supporting member.

3. A wringer bracket including a body having an upstanding standard; a bottom

wall connected to said standard and extending at an angle thereto; side walls connected to said standard and extending beyond one face thereof forming a pocket, 35 said side walls having their lower ends turned under said bottom wall; an angular flange formed on one end of said bottom wall and extending rearwardly parallel to said bottom wall providing a channel adapted to receive the supporting member and a fastening means extending through said bottom wall and rearwardly extending 40 flange positively securing said bracket onto the supporting member.

4. A wringer bracket comprising a body portion having an upstanding standard; a bottom wall connected to said standard; 50 side walls connected to the standard and extending beyond one face thereof forming a pocket; said side walls having their ends turned under the bottom of the pocket and an angular flange formed on one edge of 55 said bottom wall providing a channel pocket adapted to receive a supporting member and means for securing said bracket on said supporting member.

In testimony whereof, I have hereunto 60 set my hand at San Francisco, California, this 17th day of March, 1916.

SAMUEL F. HILGENFELD.
